COOKING RANGE

Richard A. Heck, Southfield, Montgomery Ferar, Huntington Woods, and Charles R. Russell, Southfield, Mich., assignors to Sears, Roebuck and Co., Chicago, Ill., a corporation of New York

Filed May 11, 1962, Ser. No. 70,081

Term of patent 7 years

(Cl. D81—4)

Fig. 1

Fig. 2.

Fig. 4.

Fig. 3.

FIG. 1 is a front perspective view of a cooking range embodying our new design, with a supporting cabinet for same shown therebeneath in broken lines for illustrative purposes only;

FIG. 2 is a similar view (with the cabinet omitted), showing the burner table extended and table cover retracted;

FIG. 3 is a side elevation of the range shown in the condition of FIG. 1, and

FIG. 4 is a view similar to FIG. 3, showing the range in the condition of FIG. 2.

The side not shown is substantially similar in appearance to the side shown, and the top and bottom are plain.

The dominant features of our invention reside in the portions shown in full lines.

The dial control panel is shaded to indicate color contrast.

We claim:

The ornamental design for a cooking range, as shown and described.
